(57) CLAIM

The ornamental design for a sports bag as shown and described.

DESCRIPTION

FIG. 1 is a front perspective view of a sports bag;

FIG. 2 is a back perspective view thereof;

FIG. 3 is a top perspective view thereof;

FIG. 4 is a bottom perspective view thereof;

FIG. 5 is a front view thereof;

FIG. 6 is a back view thereof;

FIG. 7 is a side view thereof;

FIG. 8 is an opposite side view thereof;

FIG. 9 is a top view thereof;

FIG. 10 is a bottom view thereof;

FIG. 11 is a perspective view thereof with the top open;

FIG. 12 is a side view thereof with the top open;

FIG. 13 is an opposite side view thereof with the top open;

FIG. 14 is a top view thereof with the top open;

FIG. 15 is a second top perspective view thereof; and,

FIG. 16 is a second top view thereof.

The broken lines are to show portions of the sports bag which form no part of the claimed design.
